UNITED STATES PATENT OFFICE.

WILLIAM K. EDGINGTON, OF OLATHE, KANSAS.

HARNESS-PAD.

SPECIFICATION forming part of Letters Patent No. 443,826, dated December 30, 1890.

Application filed April 12, 1890. Serial No. 347,613. (No model.)

To all whom it may concern.

Be it known that I, WILLIAM K. EDGINGTON, a citizen of the United States, and a resident of Olathe, in the county of Johnson and State of 5 Kansas, have invented certain new and useful Improvements in Harness-Pads; and I do declare the following to be a full, clear, and exact description of the invention, such as will enable others skilled in the art to which it applies to make and use the same, reference being had to the accompanying drawings, and to letters of reference marked thereon, which form a part of this specification.

Figure 1 is a longitudinal section of my 15 improved harness-pad, and Fig. 2 is a transverse sectional view of the same. Fig. 3 is a perspective view.

This invention relates to certain improvements in harness-pads; and it consists in the 20 novel construction and combination of parts hereinafter described.

In the embodiment of my invention I employ a core *v*, of spring rubber, having the exact shape of the form **B** used. The rubber 25 core is formed with longitudinal concave

groove *z* of depth to render the core perfectly elastic without undue solidity, and when said core is introduced into the cavity of the pressed leather form, an outer piece of leather of the proper shape is stitched over 30 the openings and the core of the pad to the flanges *o* and ends *e* of said form in order to inclose securely the rubber core.

Having described this invention, what I claim, and desire to secure by Letters Patent, 35 is—

The harness-pad consisting of the spring-rubber core having the longitudinal concave groove tapering in the direction of its cross-section inward and flaring outward at its open 40 side, said core being directly incased by a leather covering placed immediately next to the core, substantially as and for the purpose set forth.

In testimony whereof I affix my signature in 45 presence of two witnesses.

WILLIAM K. EDGINGTON.
